UNITED STATES PATENT OFFICE.

MONROE C. KIRKPATRICK, OF FILES VALLEY, TEXAS, ASSIGNOR OF ONE-FOURTH TO TIM KIRKPATRICK AND ONE-FOURTH TO WILLIAM M. SHIPPEY, BOTH OF ELLIS COUNTY, TEXAS.

AIR-SUPPLY-VALVE ATTACHMENT.

1,349,210.

Specification of Letters Patent. Patented Aug. 10, 1920.

Application filed January 24, 1918. Serial No. 213,457.

To all whom it may concern:

Be it known that I, MONROE C. KIRKPATRICK, a citizen of the United States, residing at Files Valley, in the county of Hill and 5 State of Texas, have invented certain new and useful Improvements in Air-Supply-Valve Attachments, of which the following is a specification.

This invention relates to certain improvements in air supplying attachments for carbureters.

It is customary in certain makes of carbureters now in common use to control the admission of air by a valve which is mechanically operated in conjunction with the 15 throttle valve, therefore the fluctuation of the suction created by the engine does not affect the air supply and such air supply must be regulated by the driver.

20 It will be seen under certain conditions it is highly advantageous to automatically supply an increased volume of air to the carbureter and by so doing the efficiency of the motor is increased. The idea involved 25 in this invention is to provide an attachment which may be readily connected with the air inlet of a carbureter whereby a certain amount of air is constantly admitted when the air valve of the carbureter is open, but 30 providing means for increasing the volume of air when adjusting the air valve of the carbureter and to do so in a particular manner.

In carrying out the invention a collar is 35 provided and formed with a transverse partition having a central valve sleeve. The partition is perforated to permit the passage of air therethrough, but the sleeve is normally closed and the passage of air 40 therethrough obstructed. The sleeve is interposed between the air admitting opening of the carbureter and the usual air heating pipe or the latter may be omitted. Under normal conditions the air is supplied 45 through the perforations, but an increased suction will unseat a valve in the sleeve and thus admit an additional supply of air without adjusting the air valve of the carbureter.

The invention will be more readily understood from a reading of the following specification and by reference to the accompanying drawings, in which an example of the invention is illustrated, and wherein—

Figure 1 is a view of a carbureter with

the heating pipe connected thereto by means 55 of an attachment constructed in accordance with this invention.

Fig. 2 is a longitudinal sectional view of the attachment and component parts, and

Fig. 3 is a transverse sectional view on 60 the line 3—3 of Fig. 2.

In the drawings the numeral 1 designates a carbureter having an air inlet boss 2 in which a valve 3 is pivoted in the usual manner.

65 In applying this invention an attachment is constructed in the form of a collar 4 which fits over and receives the boss 2. A set screw 5 is mounted in the car and may be tightened so as to engage the boss and 70 fasten the collar thereon. The usual hot air pipe 6 is inserted in the other end of the collar or where such pipe is not used the collar may be left open. At the central portion of the collar a transverse partition 75 7 is secured and is provided with a central valve sleeve 8 extending from one side toward the receiving end of the car and projecting beyond the same if necessary. As shown in Fig. 2 this sleeve projects into the 80 pipe 6. The said sleeve surrounds an opening 9 in the partition and has its outer end contracted to form a seat for a ball valve 10 which is held in its seat by a coil spring 11 confined in said sleeve. The valve 10 85 is somewhat smaller than the internal diameter of the sleeve so that air might pass said valve when it is unseated. The partition 7 is provided with a plurality of spaced perforations or ports 12 surrounding the sleeve. 90

It will be seen that normally the valve 10 closes the sleeve but air may freely pass through the perforations 12 as the valve 3 of the carbureter is open. This will supply sufficient air for the operation of the engine 95 under certain conditions. However when the suction is increased and a more rarefied mixture is desirable the valve 10 will be drawn inward against the tension of its spring and an increased quantity or volume 100 of air supplied without any mechanical adjustment of the valve 3 or the throttle valve. This will result not only in a more efficient operation of the motor but in the saving of fuel and the engine will be more powerful 105 and will run better. The attachment may be readily and quickly applied or removed and is inexpensive to produce.

The foregoing description and illustration clearly express the invention, but it is to be understood that said illustration is merely an exemplification and the invention may be carried out in various ways.

What I claim is,

1. An air supply attachment for a carbureter, comprising a collar adapted to receive in one end thereof the inlet of the carbureter, said collar having its periphery imperforate and being straight and having its opposite ends open for providing a straight open ended bore, a transverse partition arranged within the collar and spaced from the ends thereof and provided with a substantially central opening and apertures surrounding the opening, a valve sleeve extending longitudinally within said collar and secured to the partition and surrounding said opening, said valve sleeve having its free end extending inwardly to provide a valve seat, a valve arranged within the valve sleeve to engage the valve seat, and a spring arranged within the valve sleeve and engaging the valve.

2. An air supply attachment for a carbureter, comprising a collar adapted to receive in one end thereof the inlet of the carbureter, means to clamp the collar to the inlet, said collar having its periphery imperforate and being straight and having its opposite ends open for providing a straight open ended bore, a transverse partition arranged within the collar and spaced from the ends thereof and provided with a substantially central opening and apertures surrounding the openings, a valve sleeve extending longitudinally within said collar and secured to the partition and surrounding said opening, said valve sleeve having its free end extending inwardly to provide a valve seat, a valve arranged within the valve sleeve to engage the valve seat, a spring arranged within the valve sleeve and engaging the valve, and a hot air supply pipe having telescoping engagement with the opposite open end of the collar.

In testimony whereof I affix my signature.

MONROE C. KIRKPATRICK.
